SOUND CONTROLLING DEVICE FOR TALKING PICTURE APPARATUS

Filed Nov. 6, 1929

UNITED STATES PATENT OFFICE

1,942,068

SOUND-CONTROLLING DEVICE FOR TALK-
ING PICTURE APPARATUS

Freeman H. Owens, New York, N. Y.

Application November 6, 1929. Serial No. 405,231

6 Claims. (Cl. 179—1)

This invention relates to improvements in sound controlling devices for talking picture apparatus, the principal object of the invention being to provide a centralized device for controlling the volume of the sounds reproduced in connection with motion pictures.

A further object of the invention is to provide, in combination with a plurality of loud speakers, means for regulating said speakers en masse or 10 individually thereby to control the volume of sound delivered by the speakers as a unit or at any given point in the layout of said speakers.

A further object of the invention is to provide, in combination with a plurality of loud speakers, 15 means whereby the entire layout of speakers or certain predetermined groups thereof, or the individual speakers of the layout may be regulated to control the volume of sound.

Other objects and advantages of the invention, 20 will appear as the description proceeds.

In the drawing accompanying this specification,

Figure 1 is a perspective view illustrating diagrammatically a battery of loud speakers and 25 the centralized control board therefor arranged according to the present invention;

Figure 2 is a diagrammatic plan view showing the relative arrangement of the controlling rheostats at the controlling station;

Figure 3 is a detail cross sectional view through 30 the control panel, taken along a line approximately corresponding with the line 3—3 of Figure 2; and

Figure 4 is a sectional view illustrating diagrammatically a picture projector and sound reproducing apparatus adapted for use with the 35 present invention.

The same characters of reference designate the same parts in the different figures of the 40 drawing.

Referring to the drawing, 1 designates a portion of a projection booth such as is usually employed in moving picture theatres, in which booth is disposed a projector unit for projecting 45 moving pictures through an opening 3 in the wall of the booth and on to a screen, (not shown). Within the booth is also disposed a sound reproducing unit 4 each of said units having the usual film supply and take up reels 5 and 6 respectively. The sound reproducing unit 4 is electrically connected with the input of a suitable amplifier 7, the output of which is connected by wires 8 and 9 with a master control rheostat 10 disposed at 50 the underside of the panel 11 of a cabinet 12 which constitutes the control station for a bat-

tery of loud speakers preferably located behind the screen on which the pictures are projected.

As shown herein the speakers are arranged in three horizontal rows A, B and C, the individual speakers of the respective rows being in vertical alignment. The control cabinet is preferably disposed at a suitable position to permit the sound director to observe the volume of the reproduced sounds emitted from the speakers, and mounted on the underside of the panel 11 are 60 a plurality of rheostats, one for each of the loud speakers, said rheostats being similarly arranged in horizontal rows D, E and F, the individual rheostats of the respective rows being in alignment transversely of said horizontal rows. Each 65 of the loud speakers is electrically connected with its corresponding rheostat; that is to say, the speakers in the A row are individually connected with the rheostats in the D row, the speakers in the B row are individually connected 70 with the rheostats in the E row, and the speakers on the C row are individually connected with the rheostats in the F row.

In addition to the arrangement of individual rheostats above described, rheostats are provided 80 for independently controlling the horizontal rows of speakers. These row-controlling rheostats are designated 13, 14 and 15 respectively in Figure 2 and are preferably disposed at the underside of the control panel 11 in horizontal alignment 85 respectively with the rows of rheostats D, E and F, the wire connections between the rheostats 13, 14 and 15 and the horizontal rows of speakers A, B and C being such that all of the speakers in any one row will be regulated as a unit by the 90 operation of the particular rheostat connected with that row.

The present invention also comprehends the provision of means for controlling as a unit all of the speakers which are in vertical alignment. 95 For this purpose a plurality of rack bars 16, one for each vertical row of aligned speakers, are mounted for sliding movement on the underside of the control panel. The operating knobs or buttons 17 of the individual rheostats of the respective horizontal rows D, E and F, which knobs of course are on the outside of the control panel, are secured on elongated shafts 18 mounted for rotation and for axial movement in said panel, 100 on the inner end of each of which shafts is secured a pinion 19, all of the pinions in alignment transversely of the horizontal rows of rheostats being adapted to mesh with a single rack bar whereby reciprocation of that particular rack bar will cause rotation of the shafts of all of the 105 110

transversely aligned rheostats so that all of such rheostats may be regulated as a unit. The shafts 18, however, are of such length that when in their innermost position the pinions 19 are out of mesh with the rack bar, as shown clearly in Figure 3, in which position the rheostats controlling the vertically aligned speakers may be individually operated. For moving the pinions into rack-engaging position, levers 20 are pivoted adjacent to said pinions, each of said levers being provided at its inner end with a shoe or cam 21 so disposed with relation to its companion pinion that when the lever is swung on its pivot in one direction its shoe will engage the end of the shaft and push the same axially, thus carrying the pinion into mesh with the rack bar in a manner which will be readily understood. The levers 20 extend through slots 21 formed in the control panel 11 and are provided at their outer ends with hand grips 22 for convenience in operation. For controlling the movement of the individual rack bars a plurality of knobs 23, one for each rack bar, are secured on shafts 24 mounted for rotation in the control panel, to the inner end of each of which shafts is secured a pinion 25 which is constantly in mesh with its companion rack bar, whereby upon rotation of the knob 23 the rack bar will be moved longitudinally thereby to regulate the transversely aligned rheostats as above described.

A signal light 26 is provided on the control panel adjacent each knob 23, and is suitably connected in the circuit whereby the director is apprised at a glance which loud speakers are "on" and which are "off".

It will thus be apparent that the present invention provides an apparatus by means of which a plurality of loud speakers can be regulated en masse, or in units of horizontal rows, or in units of vertical rows, or individually. It will of course be understood that the invention is not limited to the particular number of speakers shown herein, since they may be multiplied indefinitely, and the details of construction and arrangement may be modified considerably without departing from the spirit of the invention as set forth in the appended claims.

I claim:

1. The combination with a plurality of sound reproducing devices disposed in parallel horizontal and vertical rows, of a rheostat in electrical connection with all of said devices for regulating the volume of them simultaneously, independent rheostats in connection with the respective horizontal rows for simultaneously regulating the volume of all of the devices in either of said rows, and means for simultaneously regulating the volume of all of the devices in either of the vertical rows.
2. The combination with a plurality of sound reproducing devices disposed in parallel horizontal and vertical rows, of a rheostat in electrical connection with all of said devices for regulating the volume of them simultaneously, an individual rheostat connected with each of said devices for regulating the volume of it independently of all the others, a rheostat connected with the devices in each of said horizontal rows for regulating the volume of each row independently, and independent means connect-

ing the individual rheostats corresponding to the respective vertical rows for simultaneously regulating the volume of all of the devices in either of said vertical rows.

3. The combination with a plurality of sound reproducing devices disposed in parallel horizontal and vertical rows, of a rheostat in electrical connection with all of said devices for regulating the volume of them simultaneously, an individual rheostat connected with each of said devices for regulating the volume of it independently of all the others, a rheostat connected with the devices in each of said horizontal rows for regulating the volume of each row independently, independent means connecting the individual rheostats corresponding to the respective vertical rows for simultaneously regulating the volume of all of the devices in either of said vertical rows, and means for selectively operating said connecting means.

4. The combination with a plurality of sound reproducing devices disposed in parallel horizontal and vertical rows, of a rheostat in electrical connection with all of said devices for regulating the volume of them simultaneously, an individual rheostat connected with each of said devices for regulating the volume of it independently of all the others, a rheostat connected with the devices in each of said horizontal rows for regulating the volume of each row independently, a slidable rack for each of said vertical rows, a pinion carried by the actuating member of each of said individual rheostats, all of the pinions corresponding to each vertical row being normally out of mesh with their respective rack bars, and means for selectively moving the pinions into rack bar engaging position.

5. The combination with a plurality of sound reproducing devices disposed in parallel horizontal and vertical rows, of a rheostat in electrical connection with all of said devices for regulating the volume of them simultaneously, an individual rheostat connected with each of said devices for regulating the volume of it independently of all the others, a rheostat connected with the devices in each of said horizontal rows for regulating the volume of each row independently, a slidable rack for each of said vertical rows, a pinion carried by the actuating member of each of said individual rheostats, all of the pinions corresponding to each vertical row being normally out of mesh with their respective rack bars, and pivoted levers for selectively moving the pinions into rack bar engaging position.

6. The combination with a plurality of sound reproducing devices disposed in parallel horizontal and vertical rows, of a control station disposed in proximity to said devices, said station having a master control rheostat adapted to control the volume of all of said devices as a unit, a rheostat for each horizontal row of devices adapted to control the volume of its row as a unit, individual rheostats for controlling the volume of all of said devices independently, and means for actuating the rheostats corresponding to all of the devices in either of said vertical rows independently of the other rows.

FREEMAN H. OWENS. 145
